SIDE WALL CORE TAKING APPARATUS

John R. Yancey and Earl J. Robishaw, Houston, Tex., assignors, by mesne assignments, to A-1 Bit & Tool Company, a corporation of Texas

Application December 17, 1945, Serial No. 636,936

8 Claims. (Cl. 255—1.4)

1

This invention relates to core taking apparatus. One of the purposes of this invention is to provide apparatus whereby cores, or samples, may be cut from the side walls of bore holes. These samples are very desirable as they furnish information necessary in the proper development of natural resources by supplying geophysical data. The invention also has wide application when used in connection with well logging by electrical means in that it provides samples of prospective producing formations to be examined after the well has been drilled; the device can also be used to complete coring records in wells where cores have been made by conventional methods.

Another object of the invention is to provide in core taking apparatus a novel type of whip stock, or deflector, for deflecting the core barrel into the formation.

It is another object of the invention to provide in core taking apparatus a novel type of whip stock which is adapted to engage with the core barrel to withdraw the core barrel from the well should it become detached from the apparatus during the core taking operation.

It is another object of the invention to provide a core taking apparatus including a whip stock, or deflector, all assembled with a drill stem and wherein the whip stock is suspended from, and the core barrel is driven by, said stem but wherein the core barrel is independently insertable into and withdrawable from the stem while the stem remains in the well bore.

It is a further object of the invention to provide novel means for interrupting the inflow of the drilling fluid through the apparatus to indicate to the operator that the core barrel is fully extended, with means for permitting the resumption of the flow of said drilling fluid, should pressure develop in the well which it becomes necessary to overcome, or for any other reason.

A still further object is to provide a novel method of obtaining side wall cores.

With the above and other objects in view the invention has particular relation to certain novel features of construction, operation and arrangement of parts, and to a novel method of taking cores, an example of which is given in this specification and illustrated in the accompanying drawings, wherein:

Figures 1, 2 and 3 are, upper, intermediate and lower sections of the apparatus shown in section.

Figure 4 is a longitudinal sectional view of the core barrel.

2

Figure 5 is a lower end view thereof.

Figure 6 is a cross-sectional view taken on the line 6—6 of Figure 1.

Figure 7 is a cross-sectional view taken on the line 7—7 of Figure 2.

Figure 8 is a cross-sectional view taken on the line 8—8 of Figure 3.

Figure 9 is a cross-sectional view taken on the line 9—9 of Figure 3, and

10 Figure 10 is a side view of the core taking apparatus in position to begin the operation.

Referring now more particularly to the drawings, wherein like numerals of reference designate the same parts in each of the figures, the 15 numeral 1 designates a tubular drill stem which extends to the ground surface. The lower end of the drill stem is formed with a special tubular driving section 2 which is connected thereto by the coupling 3. The section 2 has a plurality of 20 inside longitudinal ribs 4 extending from the upper to the lower ends thereof and spaced apart.

Connected to the lower end of the special section 2 there is an inwardly thickened reducing nipple 5 and connected to the lower end of the 25 nipple 5 there is a coupling 6 which contains an annular seal ring 7 for a purpose to be herein-after explained. Between the nipple 5 and the coupling 6 there is an inside gland 8 which breaks the joint between them. One end of this 30 gland abuts the opposing end of the seal ring 7 and its other end abuts an inside annular shoulder 9 in the nipple 5. The opposite end of the seal ring 7 abuts an annular shoulder 10 in the coupling 6 so that when the coupling 6 is screwed 35 onto the nipple 5 the seal ring 7 will be placed under the required compression. The passage-way through the above described assembly of the nipple 5 and coupling 6 is of substantially the same inside diameter throughout. The section 2, coupling 3, nipple 5 and coupling 6 form parts of 40 the drill stem.

The whip stock, or deflector, is designated generally by the numeral 11. It has a swivelling connection with the drill stem. This connection is 45 formed between the tubular nipple 12, whose upper end is connected to the coupling 6, and the tubular housing 13 whose lower end is connected to the whip stock 11. The lower end of the nipple 12 extends into the housing 13 and within said housing is enlarged forming the external annular upwardly facing shoulder 14 which supports an anti-friction bearing assembly 15 which is retained in place by the gland 16 screwed into the upper end of the housing 13. Countersunk 55 into the gland and surrounding the nipple 12 is

a seal ring 17 and beneath said seal ring there are the roller bearings 18 mounted in the gland around the nipple 12. The lower end of the nipple 12 is supported on the anti-friction bearing assembly 19, which, in turn, is supported on an inside annular shoulder 20 formed by the inwardly thickened lower end of the housing 13. Between the lower end of the nipple 12 and said housing there are the radial roller bearings 21 which are countersunk into said nipple and countersunk into the inwardly thickened lower end of the housing there are the annular seal rings 22. Screwed into the lower end of the nipple 12 there is an annular stop, or seat, 23 which has a depending sleeve 24 which extends down through and forms seals with the seal rings 22. An efficient swivel connection is thus formed between the drill stem and the whip stock whereby the latter is supported in the well by the former.

The whip stock, as a whole, is shown in detail in Figures 2, 3, 7, 8, and 9. It comprises a tubular shell 25 whose lower end is downwardly tapered and above said taper is provided with a longitudinal side slot 26, which extends to said lower end.

Secured on the outside of the shell opposite said slot there is a longitudinal rib 27 and on opposite sides of the slot there are the longitudinal ribs 28, 28 which are secured to the outer side of the shell. These ribs 27 and 28 engage the formation of the well bore to hold the whip stock centered in the bore hole. Within the shell 25 there is a guide which is rectangular in cross-section, as shown in Figure 7. This guide is fitted downwardly within the shell and is composed of the side plates 29, 29, whose margins are beveled to fit within the shell, and the cross plates 30, 30. The plates 29 and 30 are secured together preferably by welding. This guide is preferably flared downwardly as indicated in Figures 2 and 3. The plates 29 carry a transverse stop 31 which rests on a corresponding transverse stop 32 carried by shell 25 to support the guide in the shell. Within the shell, and arranged at the lower end thereof, is a deflector plate assembly comprising the upper plate 33 which is mounted on the lower plate 34. This assembly is arranged opposite the slot 26 and declines forwardly. It is supported by the transverse upper and lower pins 35 and 36 which extend transversely through the lower plate 34 and whose ends are anchored to the respective side plates 29. The lower pin 36 is shearable for a purpose to be hereinafter stated. The upper face of this plate assembly is provided with the roller bearings, as 37, as illustrated in Figure 3. At the upper end of the plate assembly there is secured in the guide a transverse filler block 38 which is triangular in vertical cross-section and whose upper face is approximately flush with the upper face of the deflector plate assembly, as also shown in Figure 3.

Anchored to the front plate 30 of the guide, above the slot 26, there is a spring 39 whose lower end is free and is outwardly turned through the upper end of the slot 26. The slot 26 extends on down and partly across the lower end of the shell 25, for a purpose which will be hereinafter explained, and the lower end of said slot beneath the lower end of the deflector plate assembly, above described, is closed by a thin metallic skirt 40, as shown in Figure 3, to prevent the entrance of foreign matter into the whip stock shell beneath said deflector plate assembly. The core taker proper will now be described in detail:

Generally speaking it comprises a core barrel 41 and a sectional driving stem consisting of the upper tubular section 42 and the lower tubular section 43. These sections are connected by a universal coupling designated generally by the numeral 44 and the core barrel is connected to the lower end of the section 43 by a similar universal coupling 45. Only one intermediate section of the driving stem is illustrated although it is apparent that this number may be varied if found to be practical. The upper section of the driving stem is formed of the upper and lower tubes 46 and 47, the latter of which is of slightly less diameter than the former. These tubes are connected by an inside coupling 48 which is formed with an external annular stop 49 of a diameter to land on and be supported by the internal stop 23. Screwed onto the upper end of the tube 46 there is a head 50 which has a longitudinal radially extended driving lug 51 adapted to work between the inside ribs 4 of the driving section 2. The upper end of the head 50 carries a knob 52 provided to be engaged by a grapple which may be lowered through the drill stem by means of a wire line. Screwed into the upper end of the tube 46 there is a valve seat 53 having an axial fluid passageway therethrough whose upper end terminates in a lateral port 54 through said head and the flow of fluid through this valve seat is controlled by a downwardly opening valve 55 which is mounted on a strong coil spring 56. This spring is supported on a vertically adjustable spring seat 57 which has a threaded connection with a spider 58 mounted in the tube 46. The compression of the spring 56 may thus be regulated by adjusting the seat 57. Beneath the spider 58 the upper end of the tube 46 is provided with an inlet opening 59. Located within the upper end of the reduced tube 47 there is a tubular screen 60 of smaller diameter than the tube 47 and perforated throughout its length. Its lower end is anchored to and extends through a suitable anchor 61 which is slidably mounted in tube 47. This screen 60 is provided for the purpose of screening out any solid material from the fluid flowing downwardly through the driving stem of the core taken. The universal couplings connecting the sections of the driving stem and connecting the driving stem to the core barrel are similar, as hereinabove indicated, and are shown more in detail in Figure 4. Similar flexible tubes, as 62, extend axially through these couplings and the ends of these flexible tubes are anchored in place by means of wedge shaped jaws, as 63, whose inner surfaces are toothed to engage the corresponding ends of the tubes 62 and whose outer surfaces are tapered, or wedge shaped, to be contracted by the surrounding inwardly tapering seats, as 64. The ends of the flexible tube 62 are countersunk into glands, as 65, which are screwed into the corresponding parts of the driving stem. The ends of the flexible tubes 62 are maintained against collapsing by tubular nipples, as 66, whose inner ends extend into the corresponding ends of the flexible tubes and whose outer ends are screwed into the corresponding glands 65. The detailed construction of the core barrel is shown in Figure 4. The upper end of the barrel is screwed onto the coupling member 66a and screwed into the lower end of the barrel there is a core forming tool, or drill, 67 having a central core receiving opening 68 and around said central opening there is the annular upwardly facing inside shoulder 69 which supports the sample container. This sam-

ple container is preferably cylindrical in shape and in the present illustration is shown as formed of the upper, intermediate and lower sections 10, 71 and 72 which may be assembled together in any preferred manner so that they may be conveniently separated. The lower section 72 rests on the shoulder 69 and within it, and also resting on said shoulder, there is a core catcher which comprises the ring 73 and the upwardly converging flexible fingers 74 whose lower ends are secured to said ring and whose upper ends are free. The intermediate section 71 has an inside downwardly converging seat 75, above the fingers 74. Above the seat 75 there is a core catcher comprising the expansible dogs 76 whose outer sides are tapered to conform to the taper of and to rest on said seat and whose inner sides are toothed to engage the core entering the sample container. These dogs 76 are secured to the lower ends of the corresponding flexible arms 77 which depend from the tubular shell 78. Secured to and upstanding from this shell are the upwardly converging flexible fingers 79 whose upper ends are free. As the core enters the fingers 74 and 79 will yield outwardly to permit its passageway but will thereafter engage with the core, or sample, to hold it in the sample chamber 80 of the container. If hard formation is being encountered the core can readily pass through between the dogs, or slips, 76 as they will be lifted off of the seat 75 and allowed to open to permit the passage of the core but upon entrance of the core they will seat and contract and grip the core to prevent it from falling out upon removal of the barrel from the well. Fastened onto the upper end of the sample container there is a cap 81 having a central opening surrounded by an annular seat 82 which is clamped in place on the cap by means of the perforated valve cage 83 which contains an upwardly opening valve 84. This valve normally keeps the upper end of the container closed but will lift to permit the escape of the contents of the chamber 80 as the core, or sample, enters said chamber. The upper end of the valve cage 83 abuts the lower end of the gland 65 to prevent the sample container from lifting off of its seat during the core taking process and the lower end of this gland has side slots 85 so that the passageway for the drilling fluid will not be closed by said valve cage.

In operation the operating string may be lowered to the desired location in the well so as to locate the whip stock at the point where a sample is to be taken, as shown in Figure 10. The sample taker may then be dropped through the string; or it may be lowered through the string by a wire line. The lower end of the core barrel will land on and be deflected by the deflector plate assembly of the whip stock, as also indicated in Figure 10. The flexible guide 39 will operate to guide the core barrel and hold it in the proper angular relation. When lowered to the position to begin taking a core the operating string may be rotated and the whip stock will be held against rotation by the engagement of the core cutter head 67 with the formation while the core taker will be rotated by the engagement of the driving section 2 with the lug 51 of the head 50. Fluid pressure may be applied, by a pump at the ground surface, through the operating string and against the head 50 thus gradually forcing the core taker downwardly as it is rotated and a bore will be formed by the drill 67 in the sidewall of the well bore and a core, or sample, will be taken and forced into the chamber 80, as hereinabove ex-

plained. While the coring operation is being carried on fluid will enter the stem 42, of the sample taker, through the opening 59 and pass on down through the stem and through the screen 60 in the stem and on down around the sample container to the drill 67 to lubricate and cool said drill and carry away the cuttings. When the sample taker has reached the limits of its downward movement the stop 49 will land on the seat 23 and at the same time the inlet opening 59 will enter the seal ring 7 so as to stop the flow of the drilling fluid to stall the pump and to indicate to the operator that the core barrel has reached the limit of its downward movement. However, under these conditions should gas pressure be encountered in the well the pressure in the operating string may be increased by the pump sufficiently to overcome the resistance of the spring 56 and the valve 55 thus opened to permit a resumption of the circulation of the drilling fluid under high pressure to overcome the gas pressure in the well.

Attention is called to the fact that while taking the core the deflector is suspended from the operating string and is held at substantially the same level during the coring operation and therefore means for anchoring the deflector to the walls of the bore hole are not necessary and are dispensed with. During the coring operation the string is rotated to rotate the coring apparatus but is not moved downwardly in the bore hole.

In carrying on coring operations the core barrel 41 may become detached from the apparatus and for that reason the upper end of said barrel 35 is enlarged forming an external annular shoulder 99 and the lower end of the slot 26 is narrowed and the lower end of the barrel is of a diameter to fit snugly through the narrowed end of the side slot 26, so that should said barrel become detached it will not be lost in the well but upon upward movement of the whip stock the pin 36 will be sheared and the deflector plate assembly will swing on the pin 35 to vertical position and the thin skirt 40 will be displaced and the lower end of the whip stock on opposite sides of the slot 26 will engage the shoulder 99 and the core barrel 41 will be withdrawn as the apparatus is removed from the well bore.

The drawings and description disclose what is now considered to be a preferred form of the invention by way of illustration, merely, while the broad principle of the invention will be defined by the appended claims.

What we claim is:

1. In a core taking apparatus for wells, a whip-stock comprising, a tubular shell having a longitudinal side slot which extends downwardly to the lower end of the shell, a diagonal deflector in the shell opposite said slot and which declines toward the slot, upper and lower means for anchoring the deflector in the shell, the lower anchoring means being frangible to release the lower end of the deflector, in response to inward pressure thereagainst, to allow the deflector to move to approximately vertical position in the shell.

2. Sample taking apparatus for wells comprising; a whipstock having a deflector, a tubular operating string having a rotatable connection with the whipstock and having an inside stop; a sample taker including a barrel and driving stem adapted to be lowered through the string into co-operating relation with the deflector to deflect the barrel, a seal around the stem and between it and the string to deflect fluid from

the string into the stem, said sample taker having a channel for fluid therethrough and also having an external stop arranged to land on said internal stop to arrest the downward movement of the sample taker, and means associated with said stem cooperating with said seal to close said channel when said sample taker lands in said arrested position.

3. Sample taking apparatus for wells comprising; a deflector, a tubular operating string having a rotatable connection with the deflector and having an inside stop; a sample taker including a barrel and driving stem adapted to be lowered through the string into co-operating relation with the deflector to deflect the barrel, said sample taker having a channel for fluid therethrough and also having an external stop arranged to land on said internal stop to arrest the downward movement of the sample taker and co-operating means between the string and stem to close said channel when the core taker lands in said arrested position.

4. Sample taking apparatus for wells comprising; a deflector, a tubular operating string having a rotatable connection with the deflector and having an inside stop; a sample taker including a barrel and driving stem adapted to be lowered through the string into co-operating relation with the deflector to deflect the barrel, said sample taker having a channel for fluid therethrough and also having an external stop arranged to land on said internal stop to arrest the downward movement of the sample taker, co-operating means between the string and stem to close said channel when the core taker lands in said arrested position and valve means responsive to an increase of fluid pressure, exerted through the string, to open said channel and permit a resumption of flow of fluid through said channel.

5. Core taking apparatus for wells comprising: a whipstock adapted to be connected to an operating string and including a shell having a longitudinal side slot which extends downwardly to and at least partially across the lower end thereof; a diagonal deflector within said shell opposite the upper portion of and declining toward said slot, that portion of said slot extending below said deflector being narrowed; means for supporting said deflector from said shell for movement into a substantially vertical position adjacent the wall of said shell opposite said slot in response to a predetermined inward force against said deflector; a core taker including a flexible stem and a barrel having an external rearward enlargement, said core taker being adapted to be lowered, as a unit, into said whipstock and into engagement with said deflector for deflecting said barrel through said slot into the side wall formation of the well, said barrel enlargement being of a size to prevent passage thereof through said narrowed portion of said slot, whereby upward movement of said shell relative to said barrel, when the latter is in its side wall engaged position, is effective to move said barrel into the narrowed portion of said slot and thence into a substantially vertical position within at least the projected periphery of said shell for upward movement by the latter.

6. Core taking apparatus for wells compris-

ing: a whipstock adapted to be connected to an operating string and including a shell; a downwardly sloping deflector therewithin; means defining a longitudinal side slot in said shell opposite and extending below said deflector and at least partially across the lower end of said shell; means for supporting said deflector for movement into a substantially vertical position adjacent the wall of said shell opposite said slot in response to a predetermined inward force against said deflector; a core taker including a flexible stem and a barrel having an external rearward enlargement, said core taker being adapted to be lowered into said whipstock and into engagement with said deflector for deflection of said barrel through said slot into the side wall formation of the well, said enlargement being of a size to prevent passage thereof through said slot and to effect movement of said barrel into a substantially vertical position within at least the projected periphery of said shell upon upward movement of said shell relative to said barrel.

7. Core taking apparatus for a well comprising: a whipstock having a diagonal deflector; a tubular driving member swivelly connected to said whipstock and adapted to be fixedly secured to the lower end of a tubular operating string; a core taker including a barrel and a flexible driving stem, said core taker being adapted to be lowered, as a unit, through the string and said driving member into engagement with said deflector for deflection of said barrel into the side wall formation of the well; and interfitting means on said stem and said driving member for effecting rotation of said core taker by rotation of the string while permitting relative axial movement between said core taker and said driving member.

8. The structure defined in claim 7 including sealing means about the stem for preventing escape of drilling fluid from the string into the whipstock and means defining a restricted passageway through said stem and barrel for conducting drilling fluid from the string to the side wall engaging face of said barrel, the pressure differential caused by said restricted passageway being effective to exert a force on said stem to urge the core taker against the side wall.
